UNITED STATES PATENT OFFICE

HENRY E. KIEHLBAUCH, OF TYNDALL, SOUTH DAKOTA

WHEEL-HUB PROTECTOR

Application filed March 22, 1930. Serial No. 438,150.

This invention relates to new and useful improvement on wheel hub protectors and more particularly to a device of this character which is intended for use especially on the 5 wheels of agricultural machinery such as cultivators, planters or tractors, but it is to be understood that a hub protector in accordance with this invention may be mounted on the wheels of any device for which same is 10 found adapted and desirable.

The primary object of the invention is to provide, in a manner as hereinafter set forth, a hub protector of the aforementioned character which may be expeditiously mounted on 15 a wheel of conventional construction without the necessity of altering the same in any manner and which will effectively prevent dirt, mud or sand from falling from the wheels on to the inner portion of the hub and thus getting 20 into the wheel bearings and causing the premature wearing thereof.

Another important object of the invention is to provide a hub protector of the character set forth embodying a construction which 25 will prevent mud or weeds from accumulating on the protector itself.

A further object of the invention is to provide a hub protector of the character described which will be simple in construction, 30 strong, durable, efficient in its use and which may be manufactured at low cost.

All of the foregoing and still further objects and advantages of the invention may 35 become apparent from a study of the following specification, taken in connection with the accompanying drawings wherein like characters of reference designate corresponding parts throughout the several views, and wherein:—

40 Figure 1 is a view in elevation looking at the outer side of the hub protector.

Figure 2 is a view in elevation looking at the inner side of the hub protector.

45 Figure 3 is a cross sectional view taken centrally through the device showing the same mounted in position on a wheel.

Figure 4 is a view in top plan of the protector.

50 Referring to the drawings in detail, it will be seen that the reference numeral 1 design-

nates a flat metallic disk which is provided with a centrally disposed opening for the passage of the hub 2 of the wheel. As clearly illustrated in Figure 3 of the drawings, the disk 1 is disposed on the inner side of the 55 wheel and is secured to the spokes 3 through the medium of the U-bolts 4 and the nuts 5 which are threaded on said U-bolts.

A frusto-conical sleeve 6 has its smaller end extending through the opening in the 60 disk 1 and provided with an integral out turned flange 7 for retaining said sleeve on the disk. It is to be understood that additional means, such as soldering, welding or rivets may be provided for securing the sleeve 65 on the disk if it is so desired.

The frusto-conical sleeve 6 extends inwardly over the inner portion of the wheel hub and over the outer portion of the retainer 8. 70

A metallic annulus 9 is provided with an 75 inturned integral flange 10 on its outer marginal edge for abutting engagement with the disk 1 and the opposite marginal edge of said annulus is mounted on an intermediate portion of the sleeve 6. The annulus 9 may be secured to the disk 1 and the sleeve 6 by any suitable means, such as soldering or welding.

In use, dirt, mud etc. will fall from the 80 wheel on to the protector and the annulus 9 will prevent the same from lodging in the acute angle formed by the sleeve 6 and the disk 1. The annulus 9 will also prevent weeds from winding on the sleeve 6 and binding 85 between said sleeve and the disk 1 by reason of the acute angle between the disk and the sleeve. This constitutes a most important feature of applicant's invention as it will be readily seen that the tapered sleeve would

90 direct the weeds toward the disk. It will further be seen that the disk 1 will effectively prevent mud and dirt from being deflected from the protector through the spokes 3 where it will collect between said spokes and on the outer portion of the wheel hub. It 95 will still further be seen that the portion of the sleeve 6 which projects beyond the annulus 9 will prevent mud, dirt or sand from falling off of the inner side of the annulus on to the retainer or axle of the vehicle. 100

It is believed that the many advantages of a wheel hub protector constructed in accordance with this invention will be readily understood, and although the preferred embodiment of the invention is as illustrated and described, it is to be understood that changes in the details of construction may be had which will fall within the scope of the invention as claimed.

What is claimed is:—

10. 1. A wheel hub protector of the character described comprising a plate adapted to be mounted on the wheel in a manner to encircle the hub, a frusto-conical sleeve mounted on the disk and extending laterally therefrom around the hub and an annulus having one end mounted on the sleeve and its opposite end mounted on the disk.
15. 2. A wheel hub protector of the character described comprising a flat metallic disk adapted to be mounted on a wheel concentrically with the wheel hub, means for detachably securing the disk to the wheel spokes, said disk having a centrally disposed opening for the passage of the hub, a frusto-conical sleeve having its smaller end extending through the opening in the disk, an integral out-turned flange on the smaller end of the sleeve engaged with the disk in a manner to retain the sleeve thereon and an annulus encircling the frusto-conical sleeve and having one of its marginal edges secured to an intermediate portion of the sleeve and its other marginal edge secured to an intermediate portion of the disk.

In testimony whereof I affix my signature.
HENRY E. KIEHLBAUCH.
